UNITED STATES PATENT OFFICE.

CHARLES H. SHEPARD, OF NEW YORK, N. Y., ASSIGNOR TO WYCKOFF, SEAMANS & BENEDICT, OF ILLION, NEW YORK, A CORPORATION OF NEW YORK.

TYPE-WRITING MACHINE.

SPECIFICATION forming part of Letters Patent No. 755,061, dated March 22, 1904.

Original application filed July 17, 1902, Serial No. 115,922. Divided and this application filed January 7, 1903. Serial No. 138,151.
(No model.)

To all whom it may concern:

Be it known that I, CHARLES H. SHEPARD, a citizen of the United States, and a resident of the borough of Brooklyn, city of New York, in the county of Kings and State of New York, have invented certain new and useful Improvements in Type-Writing Machines, of which the following is a specification.

My invention relates to carriage-release mechanism for type-writing machines of that class in which a swinging platen or carriage is employed, and more particularly to that character of machines wherein the platen is shifted for upper and lower case writing; and the object of the invention is to provide simple and efficient means for effecting a release of the carriage whether it be in the operative position or be swung back to inspect the writing.

To the above and other ends which will hereinafter appear my invention consists in the features of construction, arrangements of parts and combinations of devices to be herein-after described and claimed.

In the accompanying drawings, wherein like reference characters indicate corresponding parts in the various views, Figure 1 is a side elevation of the upper portion of a No. 6 Remington type-writing machine with the features of my invention shown and applied thereto. Fig. 2 is a side elevation of some of the parts illustrated in Fig. 1, the feed-rack being shown in the engaged position. Fig. 3 is a like view of the same, showing the feed-rack disengaged from the pinions and the platen in the operative position. Fig. 4 is an end view of the parts shown in Figs. 2 and 3, the view illustrating the platen swung back to the inoperative position and the feed-rack disengaged by the release-key. Fig. 5 is a detail perspective view of a portion of the carriage-release mechanism.

The present case is a division of my application, Serial No. 115,922, filed July 17, 1902.

The frame 1 of the machine is surmounted by a top plate 2, which has upwardly-extending lugs 3, that support a traverse-rod 4, the top plate likewise having upwardly-extending lugs 5, that support a traverse-rod 6. The truck 7 is provided with a rearwardly-extend-

ing arm 8, that is forked at its rear end for engagement with the flanged sleeve 9, supported 50 and sliding on the traverse-rod 6. The truck carries rollers 10, that are supported upon the traverse-rod 4, so that the truck is guided and supported upon the two traverse-rod 4 and 6 in its movement from side to side of the machine. The truck has links 11, pivoted thereto at 11^a, as indicated in Fig. 3, and the upper ends of these links are in turn pivoted at 12 to a platen frame or carriage 13, that supports a platen 14, which is adapted to revolve therein. The pivots 12, which unite the platen-frame to the links 11, are extended at their ends and coöperate with screw-stops 14^b to limit the backward and forward movements of the platen-frame when it is shifted for upper and lower case writing. The forward cross-bar of the platen-frame carries the roller 15, that bears upon a shift-rail 16, supported, operated, and held by any suitable shift mechanism—such, for instance, as that ordinarily employed in the No. 6 Remington machine—whereby the platen-frame carrying the platen 14 may be shifted transversely for upper and lower case writing and may be held in either the upper or lower case position. 75

The truck 7 is provided with depending ears 17, to which curved arms 18 are pivoted at 19, and these curved arms extend over the top of the traverse-rod 4 and carry at their forward ends the feed-rack 20, adapted to mesh with 80 a feed-pinion 21, fixed upon a shaft 22, that is supported in a bearing 23, carried by the top plate of the machine, and the shaft is operatively connected at its rear end to an escape-wheel 24, that coöperates with suitable 85 feed-dogs (not shown) in the usual manner.

Projecting forwardly from one end of the feed-rack is an arm 25, that terminates in a pin 26, which extends at an angle thereto and is received within an opening 27 in an angle 90 or elbow lever 28, pivoted at one end 29 to the truck. This angle or elbow lever carries a laterally-projecting headed pin 30, that carries an antifriction-roller 31. Pivoted to one end of the platen-frame, and preferably the 95 left-hand end thereof, is a release-key lever

32, the pivot of said lever being indicated at 33, and the forward end of the lever is fashioned into a finger-key 34 where it extends to the front portion of the platen-frame, whereas 5 the rear end of the lever extends beneath the antifriction-roller 31, carried by the elbow-lever 28, and is preferably rounded or curved on its upper contact-face, as indicated at 35. The release-key lever has an enlarged portion 10 36, that is slotted at 37, where it receives the stem of a headed screw 38, the stem of said screw passing through the slot and taking into a threaded opening in the platen-frame in order to guide the lever and prevent a lateral deflection thereof. A bent leaf-spring 39 is secured at one end to the platen-frame and bears at its other end against a pin 40, which projects inwardly from the enlarged portion 36 of the release-key lever, and the tension of the 15 spring is exerted to normally maintain the lever in the position indicated in Fig. 2.

From an examination of Fig. 1 it will be seen that the normal disposition of the parts is such that the release-key lever is entirely 20 disconnected and out of contact with the elbow-lever 28 and, in fact, with all portions of the truck, so that the platen-frame is free to be shifted forwardly and back to change the case position of the platen without interference 25 by the release-key lever. A depression, however, of the finger-key 34 is effective to depress the forward end of the lever against the tension of its spring, thereby elevating the rear end of the lever and bringing it into contact 30 with the antifriction-roller on the elbow-lever 28. The effect of this movement is to raise the feed-rack or to move it transversely and out of engagement with its coöperative pinion 21, as 35 illustrated in Fig. 3, thus releasing the carriage 40 from its feed mechanism. When the platen has been swung back to the position represented in Fig. 4, the relation of the parts is somewhat changed; but the inner end of the release-key lever is nevertheless in a position where 45 a depression of the release-key will cause the rear end of the lever to be moved in the direction of the arrow in Fig. 4, and this movement is effective to turn the lever 28 on its pivot, thus lifting the feed-rack from engagement 50 with its coöperating feed-pinion. It will therefore be seen that the release-key lever extends to the front of the carriage, where it may be readily grasped, and is at all times maintained in such position that it may coöperate 55 with its associated parts to release the carriage, whether the platen be in the operative position (illustrated in Fig. 3) or in the inoperative position (illustrated in Fig. 4) and without interfering with the shifting movements of the platen-frame and platen.

My invention will be found of great value in type-writing machines with swinging platens and wherein printing-point indicators are employed, inasmuch as it is desirable in such 60 machines to move the carriage when it is

swung back, as illustrated in Fig. 4, in order that the carriage may be moved at this time to bring the exact point where the insertion is to be made—for instance, into register with the printing-point indicator—and in order that 70 the registration may be readily attained while the parts are within the view of the operator and without first swinging the platen down to release the carriage and again swinging the platen back after the carriage has been moved 75 to see if the proper position has been attained.

Various changes may be made without departing from the spirit of my invention. Thus, for instance, while I have specifically described the embodiment of a laterally-movable feed-rack carried by the carriage for engagement with a feed-pinion from certain aspects of my invention any suitable coöperating feed elements may be employed, and while my invention is particularly adapted for 80 shifting-platen machines it should be understood that from certain aspects the invention is not limited to machines of that character. Then, again, I have made a distinction between the platen frame and truck throughout the 85 specification, and from certain aspects of my invention these distinctions may be regarded, whereas from certain other aspects these parts may be regarded generally as the carriage.

What I claim as new, and desire to secure 90 by Letters Patent, is—

1. In a type-writing machine, the combination of a swinging carriage which is likewise adapted to be shifted transversely for upper and lower case printing, a carriage-feed element carried by said carriage, a coöperating feed element carried by the framing of the machine, and a carriage-release key at the front of the carriage which is adapted to disengage the feed elements whether the carriage 100 be in the printing position or is swung back out of the operative position.

2. In a type-writing machine, the combination of a truck, a swinging platen-frame, a transversely-movable carriage feed-rack carried by the truck, a coöperating feed element carried by the framing of the machine, and a hand-operated carriage-release key carried by the platen-frame and extending to the front portion thereof, and at all times in coöperative relation with the feed-rack to move it transversely in order to disengage it, whether the platen-frame be swung back or is in the operative position.

3. In a type-writing machine, the combination of a truck, a swinging platen-frame connected thereto, a transversely-movable carriage feed-rack carried by the truck, a coöperating feed element carried by the framing of the machine, a carriage-release key carried 120 by the platen-frame and extending to the front portion thereof, and a pivoted device connected to the said feed-rack and operatively connected at all times to release the key, whereby the rack may be moved transversely 125 130

in order to disengage it, whether the platen-frame be swung back or is in the operative position.

4. In a type-writing machine, the combination of a truck, a swinging platen-frame which is likewise adapted to be shifted transversely for upper and lower case printing, a transversely-movable carriage feed-rack carried by said truck, a coöperating feed element carried by the framing of the machine, and a carriage-release key which is carried by the platen-frame and extending to the front portion thereof and coöperates with the feed-rack to move the same transversely to disengage the feed elements whether the platen-frame be in the printing position or is swung back out of the operative position.

5. In a type-writing machine, the combination of a swinging carriage which is likewise adapted to be shifted transversely for upper and lower case printing, a transversely-movable carriage feed-rack, a coöperating feed element, a carriage-release key carried by the carriage and extending to the front thereof, and a coöperating lever pivoted to the carriage and connected to the rack, whereby a movement of the release-key will effect a disengagement of the rack from its coöperating feed element whether the platen-frame be in the operative position or be swung back.

6. In a type-writing machine, the combination of a swinging carriage, a feed element carried by the carriage, coöperating carriage-feeding devices carried by the framing of the machine, means for shifting the platen transversely for upper and lower case printing and independently of the feed element carried by the carriage, a pivoted angle-lever connected to the feed element on the carriage, a carriage-release key carried by the carriage and in operative relation to but disconnected from the angle-lever, the relation and disposition of the parts being such that the release of the carriage may be effected through said release-key whether the carriage be in the operative position or be swung back to the inoperative position.

7. In a type-writing machine, the combination of a truck, a swinging platen-frame connected to the truck and adapted to be shifted relatively thereto for upper and lower case writing, a carriage-feed element movably mounted on said truck, an angle-lever pivoted to the truck and connected to said feed element, coöperating carriage-feeding devices carried by the framing of the machine, and a carriage-release key carried by the platen-

frame and coöperating with the said angle-lever to disengage the carriage-feed elements whether the platen-frame be in the operative position or be swung back to the inoperative position.

8. In a type-writing machine, the combination of a carriage, a carriage-feed element carried thereby, coöperative carriage-feeding devices carried by the framing of the machine, a lever pivoted to the carriage and pivoted to the feed element carried by the carriage, and a release-key carried by the carriage and extending to the front portion thereof and in operative relation to said lever whether the carriage be in the operative position or be swung back to the inoperative position.

9. In a type-writing machine, the combination of a truck, a swinging platen-frame connected to move relatively to the truck for upper and lower case writing, a laterally-movable feed-rack carried by the truck, feeding devices coöperating with said feed-rack, a release-key carried by the platen-frame and extending to the front portion thereof and disconnected from the feed-rack but in operative relation thereto, to release the rack from engagement with the said feeding device whether the platen-frame be in the operative position or be swung back to the inoperative position.

10. In a type-writing machine, the combination of a truck, a swinging platen-frame connected to move relatively to the truck for upper and lower case writing, a laterally-movable feed-rack carried by the truck, a feed-pinion with which said feed-rack meshes, an angle-lever pivoted to the truck and connected to the feed-rack, and a release-key lever pivoted to the platen-frame and disconnected from the angle-lever but in operative relation thereto whether the platen-frame be in the operative position or be swung back to the inoperative position, whereby the platen may be shifted for upper and lower case writing without interference by the release-key lever and the carriage may be released by said lever whether the platen-frame be in the operative position or be swung back to the inoperative position.

Signed in the borough of Manhattan, city of New York, in the county of New York and State of New York, this 5th day of January, A. D. 1903.

CHARLES H. SHEPARD.
